UNITED STATES PATENT OFFICE.

JAMES M. ZUMWALT, OF BUENA VISTA, FLORIDA, ASSIGNOR OF ONE-HALF TO LILLA M. ZUMWALT, OF BUENA VISTA, FLORIDA.

ADJUSTABLE TRY-SQUARE.

1,275,822.

Specification of Letters Patent. Patented Aug. 13, 1918.

Application filed August 22, 1917. Serial No. 187,661.

To all whom it may concern:

Be it known that I, JAMES M. ZUMWALT, a citizen of the United States, residing at Buena Vista, in the county of Dade and 5 State of Florida, have invented certain new and useful Improvements in Adjustable Try-Squares; and I do hereby declare the following to be a full, clear, and exact description of the invention, such as will enable 10 others skilled in the art to which it appertains to make and use the same.

The invention relates to an adjustable try-square for irregular surfaces.

The object of the present invention is to 15 improve the construction of try-squares and to provide a simple, practical and efficient try-square equipped with an irregularly shaped blade and a straight handle or stock to enable it to fit siding and the like and 20 equipped with means for enabling it to rest in proper position and lie perfectly flat upon the work so that a straight line may be accurately drawn for making a square cut.

25 It is also an object of the invention to provide a try-square of this character which will be capable of adjustment to enable it to be used for marking material for either a right or left hand cut.

30 With these and other objects in view, the invention consists in the construction and novel combination of parts hereinafter fully described, illustrated in the accompanying drawing and pointed out in the claim here- 35 to appended; it being understood that various changes in the form, proportion, size and minor details of construction, within the scope of the claim, may be resorted to without departing from the spirit or sacrificing any of the advantages of the invention.

In the drawing:

Figure 1 is a perspective view of a try-square constructed in accordance with this 45 invention.

Fig. 2 is an end view showing the arrangement of the blade upon a piece of siding with the handle or stock against the side edge of the material.

50 Fig. 3 is a plan view of a portion of a

square, the outline of the pivoted end of the blade being shown in dotted lines.

Fig. 4 is a detail sectional view illustrating the arrangement of the pin which forms the laterally projecting support.

Like numerals of reference designate corresponding parts in all the figures of the drawing.

In the accompanying drawing, in which is illustrated the preferred embodiment of 60 the invention, the try-square comprises in its construction a handle or stock 1 provided at one end with a slot or bifurcation 2 which receives the inner end 3 of an irregularly shaped blade 4 mounted on a pivot 5 and 65 adapted to swing to either side of the stock or handle 1. The pivot 5 consists of a bolt or screw equipped with a nut 6 and piercing the bifurcated end of the stock or handle 1. The nut is provided with a tail or handle 7 but any other suitable means may of course 70 be employed for enabling the nut to be turned to clamp the blade.

The blade 4, which has straight inner and outer portions, is also provided with a 75 curved connecting intermediate portion 8 and it conforms to the configuration of a piece of siding 9 so as to lie contiguous to the surface of the same with the handle or stock 1 fitting against the side edge 10 of 80 the siding. This will enable the siding to be accurately marked off for a square cut and in order to allow the blade to rest flat against the siding, the handle or stock 1 is provided with lateral projections 11 85 preferably formed by a transverse pin 12 and located in the plane of the inner portion of the blade so that one or the other of the laterally projecting supporting portions 11 will rest upon the material when the blade 90 is at either side of the stock or handle. The ordinary square, when applied to a siding, will have its blade touching the same only at the high points of the material and it is exceedingly difficult to draw an accurate line 95 to make a square cut, but by shaping the blade of the square to fit the irregular surface of the material and providing supporting means at the other end of the stock or handle, the square will rest firm and steady 100

upon the material and in proper position for accurately marking the same. The laterally projecting supports will enable the blade to be turned to either side of the 5 square.

What is claimed is:

An adjustable square comprising a stock or handle and a blade shaped to conform to the configuration of irregular material and 10 pivoted to the stock or handle at one end thereof to swing to either side of the same, and projections extending laterally from the stock or handle at the opposite end

thereof and arranged to rest upon the material in spaced relation with the blade when 15 the blade is in either position, whereby the blade will be adapted to be placed perfectly flat against the material without liability of turning while the material is being marked.

In testimony whereof I affix my signature 20 in presence of two witnesses.

JAMES M. ZUMWALT.
